UNITED STATES PATENT OFFICE.

EDWARD E. ROSE, OF EDGEWOOD PARK, PENNSYLVANIA, ASSIGNOR TO WESTINGHOUSE ELECTRIC & MANUFACTURING COMPANY, A CORPORATION OF PENNSYLVANIA.

SWITCH.

Application filed December 31, 1921. Serial No. 526,348.

My invention relates to switches and it has particular relation to switches adapted to carry relatively heavy currents.

One object of my invention is to provide 5 an improved seating device for a movable contact member that is adapted to bridge two stationary contact members.

Another object of my invention is to provide an improved switch having a main 10 contact device for normally carrying the major portion of the current that traverses the switch and an auxiliary contact device that is employed to interrupt the circuit in which the switch is located.

15 Briefly speaking, my invention, in one aspect, consists in providing a flexible coupling between a bridging contact member and the means by which it is actuated.

For a better understanding of my invention, reference may be made to the accompanying drawings.

Figure 1 of which is a view, partially in side elevation, and partially in section, of a switch constructed in accordance with my 25 invention;

Figs. 2 to 9, inclusive, are detail views of parts of the switch that is illustrated in Fig. 1 of the drawings; and

Fig. 10 is a diagrammatic view, illustrating the manner in which the various contact members of the switch illustrated in Fig. 1 are connected.

Referring particularly to Fig. 1 of the drawings, a switch 1 comprises a plurality 35 of vertical mounting bars 2, to which are secured the various portions of the switch, hereinafter more fully described.

A plurality of stationary contact members 3 and 4 may be bridged by a movable 40 contact member or brush shunt 5, which may be actuated by a piston 6, the piston being mounted within a cylinder 7. The stationary contact members 3 and 4 and the movable contact member 5 normally carry substantially all of the current traversing the switch 1.

A plurality of auxiliary contact members 8 and 9 are employed to interrupt the current which normally traverses the main contact member 5, thereby preventing arcing between the stationary contact members 3 and 4 and the movable contact member 5. The auxiliary contact member 8 is securely

mounted upon a bracket member 11 by means of a tap bolt 12.

A blow-out coil 13, which surrounds the magnetizable core member 14, is electrically connected to the auxiliary contact finger 8 by a stationary arc horn 15. The coil 13 is also connected to a contact terminal 16. 60 The contact terminal 16 is directly electrically connected to the stationary contact member 3. The stationary contact member 4 is electrically connected to a stationary contact terminal 17—which is illustrated only 65 in Fig. 10 and which is situated on the opposite side of the switch—by means of a bracket member 18, of which the stationary contact member 4 constitutes a part. The movable auxiliary contact member 9 is securely mounted upon a contact-holding member 19 by means of a tap bolt 21. The tap bolt 21 also serves to attach an arc horn 22 to the holding member 19.

The contact-holding member 19 is pivotally 75 mounted upon a rocker arm 23 by means of a bolt 24. The contact-holding member 19 and the rocker arm 23 are biased in predetermined angular relation by means of a pivotally-mounted rod 25 and a resilient 80 member or spring 26 which is mounted thereon and positioned between the contact-holding member 19 and the rocker arm 23.

The rocker arm 23 is pivotally mounted 85 upon a rod 27 by means of a bolt 28. The rocker arm 23 is also pivotally connected to a stationary supporting member 29 by means of a bolt 31. The rod 27, which is further illustrated in Figs. 8 and 9, is mechanically connected to the piston 6 by means 90 of a piston rod 32 and a coupling member 33.

The movable contact member 5, which is commonly termed a brush, comprises a plurality of sheets of conducting material, such, for example, as copper, which are bound together by means of a plurality of blocks 35 and 36 and bolts 37.

A lower-spring-holding member 38, having a threaded portion 39 to adapt it to fit in the block 36, which is best illustrated in 100 Figs. 6 and 7 of the drawings, is also provided with a spiral groove 41 and a socket or cavity 42. (See Figs. 4 and 5.) An upper spring-holding member 42 is provided with a threaded cavity 43, whereby the member 42 is adapted to be mounted upon

the rod member 27, which is best illustrated in Figs. 8 and 9 of the drawings.

The upper spring-holding member 42, which is best illustrated by Figs. 2 and 3 of the drawings, is also provided with a spirally-wound groove 44. A relatively flat annular plate 45 is mounted upon the rod 27, above the spring-holding member 42. The plate 45 is maintained in engagement with the spring-holding member 44 by means of a nut 46. A projection 48 of the member 42 is adapted to fit into the socket 42a of the member 38 and a resilient member or spring 47 is wound upon both of the spring-holding members 38 and 42 in the spiral grooves 41 and 44 respectively and is of sufficient strength to securely bind the members 38 and 42 together. The spring-holding members 38 and 42 and the spring 47 are thus so arranged as to form a ball-and-socket joint between the rod 27 and the main contact member 5.

When fluid pressure is applied to the piston 6, the force is transmitted thereby through the piston rod 32, coupling 33, rod 27 and the spring-holding member 42 to the spring-holding member 38, and, thence, to the block 37 and main contact member 5. The projection 48 of the spring-holding member 42 is adapted to fit in the cavity of the lower spring-holding member 38 to permit movement of the main contact member 5 in any direction. The spring 47, surrounding the spring-holding members 38 and 42, tends to resist any rocking motion of the main contact member 5 but permits sufficient movement thereof to allow the main contact member 5 to properly seat itself upon the stationary contact members 3 and 4.

When the piston 6 is actuated downwardly, a portion of the force transmitted to the rod 27 is employed to actuate the rocker arm 23 until the auxiliary contact finger 9 is brought into engagement with the auxiliary stationary contact finger 8.

The parts of the switch 1 are so designed that the auxiliary contact finger 9 engages the auxiliary contact finger 8 prior to the bridging of the stationary contact members 3 and 4 by the main contact member 5.

When the piston 6 is actuated upwardly, the main contact member 5 first separates from the stationary contact members 3 and 4, and, later, the movable auxiliary contact member 9 becomes disengaged from the auxiliary stationary contact member 8.

The arc established upon the separation of the auxiliary contact members 8 and 9 is blown outwardly upon the upper and lower arc horns 22 and 15, respectively, by means of a blow-out device comprising the previously-mentioned blow-out coil 13 and core member 14, and a plurality of pole-pieces 49, which are magnetically connected to the core member 14.

The pole-pieces 49 are securely attached to the sides of an arc box 51. The arc box 51 is pivotally mounted upon a cylindrical bracket member 52 by means of a supporting member 53. The top of the arc box 51 is provided with a flange member 54, which is secured to a bracket member 55 by means of a connecting member 56 and bolts 57 and 58.

Movement of the piston 6 is governed by means of an electromagnetic valve device 59, which is well understood in the art and need not be described further than to say that it governs the admission and release of air to the cylinder 7. The piston 6 is biased to its upper position by means of a relatively powerful spring 61, only the upper portion of which is illustrated.

Referring now to Fig. 10 of the drawings, it illustrates the manner in which the stationary contact terminals 16 are connected to the auxiliary stationary contact member 8 by means of the blow-out coil 13 and to the stationary contact member 3. The stationary contact terminal 17 is electrically connected to the auxiliary movable contact member 9 by means of a conductor 62 and to the stationary contact member 4 by means of the bracket member 18.

The purpose of the diagram of Fig. 10 is to show how a circuit comprising the terminals 16 and 17 of the switch is established when the auxiliary contact members 8 and 9 are in engagement or when the main contact member 5 bridges the stationary contact members 3 and 4.

From the above description, it is apparent that I have provided means for so mounting a contact device that is adapted to bridge two stationary contact members, that the contact device may be rocked in any direction to permit proper seating of the device upon a plurality of stationary contact members, thereby avoiding poor electrical connection between the movable contact device and the stationary contacts when their adjacent surfaces become unevenly worn.

While I have illustrated a switch in its preferred form, it is apparent that minor modifications may be made in the arrangement and construction of the parts of the switch without departing from the spirit thereof. I desire, therefore, to be limited only by the scope of the appended claims.

I claim as my invention:

1. A switch comprising in combination a plurality of stationary contact members, a movable contact member adapted to bridge said stationary contact members, means disposed to actuate the movable contact member, the actuating means and contact member being adapted to provide for the transmission of an evenly distributed pressure to the contact member in a plurality of different positions, and resilient means for retaining the contact member in engagement.

with the actuating means, said resilient means being adapted to permit the seating of the contact member in different positions.

2. A switch comprising in combination, a plurality of stationary contact members, a movable contact member adapted to bridge said stationary contact members, means disposed to actuate the movable contact member, and resilient means for retaining the contact member in engagement with the actuating means adapted to permit relative movement to provide for the seating of the contact member in different positions, said actuating means and contact member being adapted to maintain contact through a substantially constant area to provide for an equal distribution of pressure on the contact member in different positions.

3. In a switching device, the combination with a plurality of relatively stationary contact members and a movable contact member for bridging said stationary contact members, said movable member having a cavity therein, of means having a knob-like projecting portion adapted to fit in said cavity for actuating said movable member, and a resilient member surrounding said knob-like projection and attached to said movable contact member.

4. A switch comprising in combination, a plurality of stationary contact members, a movable contact member adapted to bridge said stationary contact members, means disposed to actuate the movable contact member, and resilient means for retaining the contact member in engagement with the actuating means adapted to permit relative movement, said contact member and actuating means being adapted to provide for the oscillation of the contact member in all directions and to maintain engagement throughout a substantially constant area.

5. A switch comprising in combination a plurality of stationary contact members, a movable contact member adapted to bridge said stationary contact members, means disposed to actuate the movable contact member, and resilient means for maintaining the contact member and actuating means in operative relation, said actuating means and contact member being provided with comple-

mentary engaging faces adapted to permit the oscillation of the contact member in all directions to effect the seating of the contact member in different positions.

6. A switch comprising in combination a plurality of stationary contact members, a movable contact member adapted to bridge said stationary contact members, means disposed to actuate the movable contact member, said actuating means and contact member being provided with curved engaging faces adapted to permit the movement of the contact member in substantially every direction to take different positions for the bridging of the contact members, and means for retaining the contact member in operative relation with the actuating means.

7. The combination with a movable member and an actuating member, of a helical compression spring which secures said movable member to said actuating member.

8. In a switching device, the combination with a movable member and an actuating member, of a compression spring, which secures said members the one to the other.

9. In a switching device, the combination with a movable member provided with a groove and an actuating member having a groove, of a compression spring so positioned in said groove as to fasten said members together.

10. A switch comprising in combination, a plurality of stationary contact members, a movable contact member for bridging said stationary contact members, means disposed to actuate the movable contact member, said actuating means and movable contact member being provided with curved engaging faces adapted to permit the movement of the contact member in substantially every direction to take different positions for the bridging of the contacts, means for retaining the contact member in operative relation with the actuating means, and arc horns electrically connected with said first mentioned contact members, one of said arc horns being operated by said actuating means.

In testimony whereof, I have hereunto subscribed my name this 29th day of November 1921.

EDWARD E. ROSE.
